UNITED STATES PATENT OFFICE

FRANK LA OTIS LATHROP, OF WALLINGFORD, CONNECTICUT, ASSIGNOR TO H. L. JUDD COMPANY, OF NEW YORK, N. Y., A CORPORATION OF NEW YORK.

DESIGN FOR A CURTAIN-ROD.

49,903.

Specification for Design.

Patented Nov. 14, 1916.

Application filed July 31, 1916. Serial No. 112,471. Term of patent 7 years.

To all whom it may concern:

Be it known that I, **FRANK LA OTIS LATHROP**, a citizen of the United States, residing at Wallingford, New Haven county, Connecticut, have invented a certain new, original, and ornamental Design for Curtain-Rods, of which the following is a specification, reference being had to the accompanying drawing, in which—

Figure 1 is a front elevation of a curtain

rod embodying my new design. Fig. 2 is an end view.

What I claim and desire to secure by design Letters Patent is:

The ornamental design for a curtain rod as shown.

FRANK LA OTIS LATHROP.

Witnesses:

R. FLEMING STUART,
RAYMOND H. GOFF.
